(57) **CLAIM**

The ornamental design for a surgical swivel fixation ring
device, as shown and described.

DESCRIPTION

FIG. 1 is a perspective view of a surgical swivel fixation ring
device, showing the design;

FIG. 2 is a top view of the device of FIG. 1;

FIG. 3 is a bottom view of the device of FIG. 1;

FIG. 4 is a front elevational view of the device of FIG. 1;

FIG. 5 is a left-side elevational view of the device of FIG.
1; the right-side view being a mirror image thereof;

FIG. 6 is a rear elevational view of the device of FIG. 1; and,
FIG. 7 is an enlarged partial perspective view illustrating the
ring portion of FIG. 1.
